(57) **CLAIM**

The ornamental design for a computer cabinet and stand, as shown and described.

DESCRIPTION

FIG. 1 is a perspective front view of the computer cabinet and stand showing the new design.

FIG. 2 is a perspective back view of the computer cabinet and stand showing the new design.

FIG. 3 is a front planar view of the computer cabinet and stand showing the new design.

FIG. 4 is a back planar view of the computer cabinet and stand showing the new design.

FIG. 5 is a side planar view of one of the computer cabinet and stand's two lateral sides showing the new design. The two lateral sides of the new design are equivalent in appearance.

FIG. 6 is a top planar view of the computer cabinet and stand showing the new design; and,

FIG. 7 is a bottom planar view of the computer cabinet and stand showing the new design.

The article in which the design is embodied is intended for making computer hardware, software, accessory features and the Internet accessible to individuals in a public setting whether out-of-doors or indoors.
